(57) **CLAIM**

The ornamental design for a mattress foundation bracket as shown and described.

DESCRIPTION

FIG. 1 is a perspective view of a mattress foundation bracket in a raised position.

FIG. 2 is a front view of the mattress foundation bracket.

FIG. 3 is a rear view of the mattress foundation bracket.

FIG. 4 is a right-side view of the mattress foundation bracket.

FIG. 5 is a left-side view of the mattress foundation bracket.

FIG. 6 is a top view of the mattress foundation bracket.

FIG. 7 is a bottom view of the mattress foundation bracket; and,

FIG. 8 is a perspective view of the mattress foundation bracket in a lowered position.

The broken lines in the Figures are directed to unclaimed subject matter of the mattress foundation bracket and form no part of the claimed design.

1 Claim, 6 Drawing Sheets
